DRINKING TUMBLER OR THE LIKE

Jack Bloch, Leominster, Mass., assignor to Foster Grant Co., Inc., Leominster, Mass., a corporation of Delaware

Application March 12, 1958, Serial No. 50,007

Term of patent 14 years

(Cl. D36—8)

Fig. 1 is a front elevational view of a drinking tumbler or the like, showing my new design;

Fig. 2 is a fragmentary vertical section view taken on the line 2—2 of Fig. 1; and

Fig. 3 is a bottom plan view.

I claim:

The ornamental design for a drinking tumbler or the like, substantially as shown.
